UNITED STATES PATENT OFFICE

164,175

COMBINED HANGER AND POT HOLDERS

Lillie May Johnson, Worcester, Mass.

Application December 29, 1947, Serial No. 143,395

Term of patent 7 years

(Cl. D44—29)

To all whom it may concern:

Be it known that I, Lillie May Johnson, a citizen of United States, residing at Worcester, in the county of Worcester, and State of Massachusetts, have invented a new, original, and ornamental Design for Combined Hanger and Pot Holders, of which the following is a specification, reference being had to the accompanying drawing, forming part thereof.

The figure is a perspective view of combined hanger and pot holders, showing my new design.

I claim:

The ornamental design for combined hanger and pot holders, as shown.

LILLIE MAY JOHNSON.
